DISH BASKET AND CUP RACK STRUCTURE FOR A DISHWASHER

Jack W. Claywell and Stanley O. Peterson, Wisconsin Rapids, Wis., assignors to Preway Inc., a corporation of Wisconsin

Filed July 6, 1962, Ser. No. 207,904

2 Claims. (Cl. 211—71)

This invention relates to a dishwasher and more particularly to a dish basket and cup rack structure therefor.

An object of this invention is to provide new and improved structure for holding dishes, cups, glasses, and the like during washing and drying thereof in a dishwasher.

Another object of the invention is to provide in a dishwasher in which a water spray is circulated from the sides of the dishwashser tub by spray arms, a basket with a dish holding structure which holds dishes in a generally vertical position and angled relative to the sides of the dishwasher so that sprayed water impinges on all surfaces of the dishes and one dish does not interfere with the flow of water to another.

A further object of the invention is to provide a cup rack supportable on the dish basket which has a plurality of holders spaced along the length thereof with each holder having an upwardly extending rod with an upward bend intermediate the length thereof to engage within a glass and hold the glass by two-point engagement therewith so as to limit the glass surface on which water might be retained and in which each holder has a locking member to engage within a cup supported on end to firmly hold the cup in position generally facing the emitted water spray of a dishwasher.

Another object of the invention is to provide a dishwasher having a tub with side walls in which a dish basket is mounted with means for holding dishes in a generally vertical position and angled relative to the walls to face a water spray emitted from spray arms mounted on the side walls and one or more cup racks supportable either at the sides of the basket or positionable within the interior of the basket and supported from the front and rear of the basket to hold cups and glasses facing the water spray.

Further objects and advantages will become apparent from the following detailed description taken in connection with the accompanying drawings in which:

FIG. 1 is a perspective elevational view of the dishwasher with the front door opened to show the dish basket and cup rack structure therewithin and in association with a water spray arm;

FIG. 2 is a vertical section on an enlarged scale taken generally along the line 2—2 in FIG. 1;

FIG. 3 is a vertical section taken along the line 3—3 in FIG. 2;

FIG. 4 is a fragmentary plan view of the front end of one of the baskets; and

FIG. 5 is a fragmentary perspective view of a cup rack.

While this invention is susceptible of embodiment in many different forms, there is shown in the drawings and will herein be described in detail an embodiment of the invention with the understanding that the present disclosure is to be considered as an exemplification of the principles of the invention and is not intended to limit the invention to the embodiment illustrated. The scope of the invention will be pointed out in the appended claims.

As shown in the drawings, the dishwasher comprises a casing indicated generally at 10 with a front opening door 11 and having a top wall 12 and side walls 13 and 14. Located within the cabinet is a tub having side walls 15 and 16, a top wall 17 and a bottom wall 18

2

provided with a centrally located water collecting sump 19 through which a heat exchange tube 20 extends. As disclosed in the copending application of Jack W. Claywell, Serial No. 28,895, filed May 13, 1960, now Patent No. 3,104,699, a gas burner is associated with the heat exchange tube 20 for heating water within the sump 19 to a desired temperature.

The door 11 constitutes a closure for the front of the tub and the back is closed by a wall 21.

10 Water is circulated within the tub by means of a pair of rotatable spray arms 22 and 23 mounted on walls 15 and 16 respectively. Each of these arms receives water pumped from the sump through conduits as disclosed in the application previously referred to. The water is emitted through nozzles 24 formed in the spray arms so that a water spray emits from each arm toward the center of the tub. The arms are caused to rotate about the bearings 25 and 26 due to the action of the water emitted therefrom.

15 The dishwasher has a pair of dish baskets indicated generally at 30 and 31 for upper and lower baskets, respectively, with each of the baskets being mounted for movement to a loading and unloading position overlying the open door 11. The dish basket and cup rack structure disclosed herein are equally useful with a portable dishwasher openable from the top and the disclosure of a front opening dishwasher is not intended to limit the invention contained herein, but is only for illustrative purposes.

20 The upper basket 30 has rollers 32 mounted in association with a track structure 33 at each side of the tub for withdrawal and the lower basket 31 has rollers 34 at the sides thereof for engagement with a track structure 35 located at each side of the tub for coaction in a known manner.

25 30 Each of the dish baskets 30 and 31 is of generally the same construction except for the different mounting for movement and description of the basket 30 is believed adequate to describe both baskets. The basket 40 is formed of elongate material in the form of wire lengths which are suitably coated with a plastisol with a pair of wire lengths 40 and 41 defining a front of the basket and a second pair of wire lengths 42 and 43 forming a rear wall of the basket. Each side of the basket is similar, 45 with one side being shown in FIG. 3 and having lengths 44 and 45 connected by vertical sections 46, 47 and 48 defining an open side through which the water spray can readily pass. The bottom of the basket is formed by four sets of wire lengths 50, 51, 52 and 53 which run from front to rear of the basket and are welded to the front and rear wire lengths 41 and 43.

50 55 Means are provided for holding dishes in the basket including a series of curved wire lengths such as lengths 54, 55 and 56 spaced from front to rear of the basket which are curved in the plane of the bottom. Each of these wire lengths supports a plurality of loops 57, 58, 59 and 60 spaced along the length thereof to engage both the front and rear of a dish and support the dish in a generally vertical position and angled relative to the side walls 60 of the dishwasher to expose all surfaces of the dish to the water spray emitted from the spray arms. By the term "dishes" is meant not only dishes having depth, but also relatively shallow members such as plates and the like. As will be noted in FIG. 3, the spacing between the curved wire lengths 54—56 is greater toward the rear of the basket to provide for holding a variety of dishes of differing depths.

65 70 A plurality of cup racks are provided for holding cups, glasses, and the like with the cup rack being shown in perspective in FIG. 5 embodying an elongate base member 68a to which a plurality of holders 61, 62 and 63 are secured. Each of these holders has a generally vertical

section 64 which is secured to the base member 60^a as by welding and an outwardly angled rod portion 65 having an inner section 66 and an outer section 67 at an increased angle to engage within a glass as shown in FIG. 2 and provide two-point engagement with the glass which reduces to a minimum the possible area which could retain water after the glasses are dried. The vertical section 64 of a holder is provided with a U-shaped protrusion 68 engageable within a cup positioned on end on the inner section 66 of a holder to secure a cup in position facing the water spray without any possibility of the cup being forced off the holder by the spray. The spacing of this locking member protrusion is designed to engage the inner surface of the cup wall when the cup rests on end on the holder section 66.

The cup rack may be supported in alternate positions either on the side of a basket or intermediate the sides of the basket by support from the front and rear thereof. As shown in association with the lower basket 31 in FIG. 2, the cup rack is mounted on a side of the basket. This is accomplished by having the front and rear holder of the cup rack formed with a hook 70 formed at the upper end thereof which engages the top wire member 44 of a basket. The cup rack is held in supported position by engagement of a brace rod 71 secured thereto with the vertical sections 46, 47 and 48 of a basket side.

An alternate position is shown for the cup rack in association with the upper basket 30 in FIG. 2 in which the base member 60^a of the basket rests in notches 75 formed in the front and rear wire members 40 and 42 respectively with the brace member 71 engaging a series of plate engaging loops 59 to hold the cup rack in upright position. The base member 60^a has its ends turned down as indicated at 76 to limit movement of the cup rack from front to rear relative to the dish basket.

In these various alternate positions of the cup rack it will be seen that cups and glasses are always supported facing the water spray and are held in an inclined position to make sure that no moisture is retained within the vessel. This assures proper drying of the cups and glasses by the dishwasher.

We claim:

1. A dishwasher basket and cup rack combination, comprising, a basket formed of wire stock with lengths of wire extending along the front, rear and sides thereof and

with the lengths at front and rear being notched, a cup rack including an elongate base member, a pair of hooks adjacent the ends of the base member to engage a wire length at a side of the basket, a pair of downturned ends on said base member to hold the cup rack in alternate position resting in said notches, a plurality of holders secured in spaced relation on said base member, each holder being integrally formed with a generally vertically extending section secured to the base member and an outwardly extending rod portion with an inner section at an angle to the vertical section and an outer portion of the rod being at an angle to the inner section to engage within a glass, and a protrusion formed on the vertical section above the inner section of the rod to engage within a cup resting on end on said inner section.

2. A dishwasher basket and cup rack combination, comprising, a basket formed of elongate material with lengths thereof extending along the front, rear and sides thereof, a cup rack including an elongate base member, a pair of hooks adjacent the ends of the base member to engage a side of the basket, a plurality of holders secured in spaced relation on said base member, each holder being integrally formed with a generally vertically extending section secured to the base member and an outwardly extending rod portion with an inner section at an angle to the vertical section and an outer portion of the rod being at an angle to the inner section to engage within a glass, and a protrusion formed on the vertical section above the inner section of the rod to engage within a cup resting on end on said inner section.
